(57) **CLAIM**

The ornamental design for a pole unit housing for electrical switchgear, as shown and described.

DESCRIPTION

FIG. 1 is a front perspective view of the pole unit housing;

FIG. 2 is a rear perspective view;

FIG. 3 is a front elevation;

FIG. 4 is a right side elevation;

FIG. 5 is a top plan view;

FIG. 6 is a bottom plan view;

FIG. 7 is a right side elevation; and,

FIG. 8 is a back elevation.

The broken lines shown in FIGS. 1-8 are for the purposes of illustrating unclaimed portions of the pole unit and form no part of the claimed design.
